UNITED STATES PATENT OFFICE.

HARRY BRIDGMAN SMITH, OF BROOKLYN, NEW YORK, ASSIGNOR TO LIGHTSHIP CLOTH BOARD CORPORATION, OF BROOKLYN, NEW YORK, A CORPORATION OF NEW YORK.

ART OF PAPER-WARE MANUFACTURE.

Application filed April 1, 1922, Serial No. 548,625. Renewed July 29, 1926.

My invention relates to improved and economical methods of producing hollow, or flattened tubular, articles composed largely or entirely of fibrous sheet material, such articles when made in suitable proportions being especially adapted for use as "cloth boards", that is, cores or centers upon which various cloths and other fabrics are wound for shipment, exhibition and sale, the center or core with the fabric wound upon it forming the well-known fabric "bolt" of commerce. In a more particular sense the invention relates to what I term for convenience a "continuous" method of producing articles of this character.

There are two general classes of cloth boards in general use. One is a substantially solid board made of one or more pieces of wood, pulp, or multiple layers of card-board or pulp-board, and the other is an approximately hollow board, the more inexpensive ones of which usually consist of a wooden frame covered with paper. The latter class of boards is more especially adaptable for the winding of fine fabrics such as expensive silks and the like. Such a board is considerably lighter than a solid board of similar dimensions; it is relatively thick so that ample space is afforded for end labels, which are usually essential, it may be made with rounded longitudinal edges, and since it is usually covered with paper, a smooth finish is provided which avoids injury to fine fabrics.

My invention relates to the production of boards of the general class just above described, these being known in the trade as "flapper boards", and provides for continuously advancing component materials and shaping them into cloth board form and then severing the combined materials at regular intervals to produce cloth boards of the desired lengths, after which when necessary or desirable, the open ends of the tubular boards are closed by plugs, and other finishing operations are performed whenever necessary, as sufficiently explained hereafter. This method is believed to be entirely new in the production of cloth boards or other articles of this class.

Described in general terms, the "continuous" production method in one specific example consists in advancing suitable sheet

body forming material from a roll; treating the sheet material with strengthening, hardening or stiffening agent or material, as sufficiently indicated in a general way above in connection with the product, and further explained hereafter; advancing reinforcing strips from rolls; adhesively conditioning the reinforcing strips, and then applying them in properly spaced relation to the main sheet or strip; then turning over side portions of the body strip substantially along the line of the reinforcing strips and shaping, pressing or molding these combined reinforcing and body portions to form the rounded edges of the board, bringing together the free edges of the body strip and overlapping the margins thereof, one margin being adhesively conditioned, pressing the margins to complete the tubular connection of the body, and then cutting the tubular assembly on transverse lines at intervals to produce complete hollow board bodies of the desired length. The reinforcing plugs or other reinforcements are then inserted.

The characteristics and advantages of the invention are further sufficiently explained in connection with the detail description of the accompanying drawings, which show certain representative embodiments of the method and the product. After considering these, it will be understood that many variations may be made within the principles of the invention, and I contemplate the employment of any performances of the process which are properly within the scope of the appended claims.

In the drawings:—

Fig. 1 is a perspective, diagrammatic view sufficiently representing one performance of the method.

Figure 2 is a perspective view of a forming guide or mandrel suitable for employment in the method.

Figure 3 is a transverse section of the materials at an intermediate stage of board formation.

Figure 4 is a transverse section showing mainly the means for advancing the materials or "assembly".

Figure 5 is a plan view, showing materials advancing in the performance of the continuous production method in modified

form, adopted for a different cloth-board structure.

Figure 6 is an elevation of the same.

Figure 7 is a section of a completed board 5 body at 7-7, Fig. 5.

Figure 8 is a perspective view of a completed cloth board in one form, with some parts broken away.

Figure 9 is a perspective view of one form 10 of reinforcement or end plug.

Figure 10 is a transverse section of the board.

Figure 11 is a perspective view of another form of board body, shown in this case 15 without reinforcements or end plugs.

Figure 12 is a transverse section of the same.

Figure 13 is a detail enlarged view of 20 the same form of construction.

Representative or typical forms of the cloth boards will first be described to enable the production methods to be fully understood. Figures 8, 9 and 10 sufficiently illustrate one desirable form of the board

25 in which the principal part or shell of the tubular board body B consists of suitable sheet material, usually fibrous material such as cardboard, or even in some cases a fairly stiff grade of paper may be employed. In

30 the present specific example, the shell consists of a single sheet 1 of cardboard of moderate thickness, and in certain cases this is desirably treated with a hardening, stiffening or strengthening agent or material;

35 for example, the sheet may be coated on one side with a suitable glue or glue-size or surface-coated or impregnated with a solution of sodium silicate which is afterward properly dried. The longitudinal edges or margins of sheet 1 are suitably connected, this connection being in the present instance by overlapping and adhesively securing the margins 2 and 3. The body is in flattened

40 tubular form, that is, it comprises relatively long, flat sides 4 and 5 of substantial width, and more or less rounded edges 6, these edges being very desirably, as shown in this particular example, of semi-cylindrical form.

The longitudinal edges of the body are 45 reinforced, and the reinforcements consist in the present instance of strips 7 of suitable fibrous sheet material, such as cardboard, of suitable strength and stiffness. These strips have central portions conforming to the

50 curved shape of the edges 6, and usually have marginal portions 8 extending more or less outward along the flat body sides 4 and 5, and these reinforcements are adhesively secured, usually by glue applied over the

55 entire engaging faces.

Reinforcements in the form of plugs are 60 desirably inserted at one or more places along the length of the tubular body. In many cases it is only necessary to provide

65 these reinforcements at the ends, and they

are then naturally referred to as end plugs. One such reinforcement or plug 10 is shown in Fig. 9. This is built up of a plurality of strips or laminations 11, which may conveniently be cardboard or other sheet or fibrous material, since in a factory devoted to the manufacture of fibrous sheets and articles a considerable amount of cardboard scrap will accumulate which may be advantageously used for the production of these reinforcements; and the reinforcements or plugs may therefore be produced at a very low or negligible cost for material. Otherwise the reinforcements may be of molded pulp or cellulose stock, or may be of wood cut to 70 the desired shape. Two of these plugs are shown in position within the ends of the board in Fig. 8, and adhesive has been properly applied to the engaging surfaces before the plugs are inserted, and they are therefore in this instance adhesively secured in position, although in some cases it is practicable to secure them by means such as tacks or staples driven through the sheath or body.

The completed article is of rectangular form, usually relatively long and narrow and relatively thin in relation to its width, although it must have substantial thickness so that the ends, which are exposed substantially flush with the fabric when the board 80 is in position at the center of a bolt of cloth, provide ample surface for the application of a suitable label, and also so that the article conforms in general dimensions and appearance to the standard form of boards 85 which are acceptable for certain purposes of the textile trades.

The structure requires a very small amount of material, so that there is an immense saving in the way of paper or other fibrous stock 90 required. It is remarkably stiff and strong, and in fact exhaustive tests have proved that it is amply able to resist any strain which is put upon it in use, especially in transverse directions. The edge reinforcements are 95 amply sufficient to prevent breaking or crushing of the edges in any proper or ordinary handling, and even to resist a great deal of abuse. The edges are smooth and rounded and the flat surfaces are also smoothly finished, so that there is no possibility of injury to fabrics which may be wound upon the board. In fact, the article complies with the strictest requirements of the trade, and in addition is exceedingly inexpensive considered merely from the standpoint of structure and the amount and nature of material required.

While the end plugs or reinforcements 100 above mentioned are in very many cases entirely sufficient, whenever it is necessary or desirable additional reinforcements may be provided. For example, in Fig. 8 another plug or reinforcement 10' is shown in position midway the length of the board. This 105

plug has been coated with glue and inserted by pushing in through one end and properly located and then secured by pressing the body material upon it. When additional reinforcements are provided, they of course increase the strength and stability of the board and its resistance to crushing strains.

Figs. 11, 12 and 13 show another representative structure. The tubular body in this case comprises main or facing sheets 15, of cardboard or other suitable sheet material, cooperating with external or edge reinforcing strips 16 which are substantially similar to the strip 7 previously described, except that they serve in the present instance primarily to join the main or facing sheets 15 by means of the overlapping adhesively secured margins 17. Additional strips, or outer reinforcements 18 are also desirably provided, consisting in this instance of strips of material narrower than the strips 16, being in completed form substantially semi-cylindrical in form and having their edges 19 closely fitting or abutting against the longitudinal edges of the main sheets 15. These strips 18 are adhesively secured to the underlying surface of the strips 16. In some cases the body structure is completed by edge binding strips 20 of suitable sheet material, such as paper of suitable quality, or fabric, these strips usually having margins 21 extending inward toward the line of intersection of the reinforcing strips 18 and main sheet 15, and these binder strips are also adhesively secured. End plugs or other reinforcements may be inserted in this tubular body, as in the previous example, and when necessary or desirable the ends may be additionally bound or finished by binding strips 22, adhesively applied.

A great many other variations may obviously be made in the structure. For instance, the main body wall or shell may be composed in some instances of two or more plies of material with suitable reinforcements at the edges.

One such structure is sufficiently shown in Fig. 5 (at the right) and Fig. 7. The tubular board body B' is composed of two layers or sheets 60 and 61, arranged so that the longitudinal edges of each sheet abut each other, as at 62—63, 64—65, and a marginal portion of one sheet, such as the part 66 of sheet 61, overlaps margin 67 of sheet 60. Adhesive is supplied between the contacting surfaces of the sheets, including margins 66 and 67, and the adhesive connection of these margins is a sufficient joint or bond to retain the body in tubular form, although additional reinforcement can be supplied along this joint if necessary or desirable. Edge reinforcing strips 68 are adhesively secured to inner surfaces of sheet 60. There is thus provided in a simple way additional shell-wall thickness to provide exceptional strength and durability,

without sacrifice of the resiliency and flexibility within suitable limits, inherent in the structure.

For many classes of service, however, a multi-ply shell is unnecessary, and as it is usually desirable to keep the amount of material down to the minimum for the sake of economy, in a great many cases a single main shell body sheet is sufficient, as above explained.

Edge binding strips such as 20, Fig. 12, may be applied to the boards of Fig. 8, to provide an especially smooth and safe edge surface for very delicate fabrics, or for other purposes. Many other variations will occur to persons versed in this art, in line with the principles of the invention as herein disclosed.

A cumulative economy of manufacture is provided by the present invention because of the fact that the structures as above described are adaptable for very economical production methods, and especially methods which I call "continuous" as distinguished from ordinary processes of cutting out separate blanks and folding them up and pressing them into the desired shapes, in box production and other classes of paper-ware manufacture. A typical example of such a continuous method, suitable for production of the tubular board bodies of Fig. 8, will now be described.

In Fig. 1, the sheet body material 1 of Fig. 8 is provided in the form of a roll 30, and the material is continuously advanced from this roll. Omitting for the present operations performed in some cases between the point where the sheet 1 leaves the roll 30 and the point where it is associated with reinforcing strips, the reinforcing strips 7 are provided in the form of rolls 31 and 32, and these strips are also continuously advanced from the rolls and brought into engagement with the main strip 1 at points properly spaced inward from the edges of the strip. Before the assembly engagement of the respective strips, adhesive is supplied in any suitable way, for example by running the strips 7 over glue rolls 33 so that their under surfaces are glued, and then the strips 1 and 7 are run together between pressing rolls 34 and 35. The materials, which are now in a form which may be conveniently designated as a sheet or strip assembly, are continuously advanced and by suitable means shaped into tubular form, and during this shaping the edge formation 6, as shown in the typical structure of Fig. 8, is obtained, and finally the edge margins of the sheet 1 are overlapped and secured and individual board bodies B produced by cutting the assembly transversely at regular intervals. It should be understood that the word "continuous" as applied to the production method does not necessarily mean uninterrupted

movement of the separate materials or of the assembly, since in some cases this movement may be intermittent; but it applies more especially to the generally steady advance and progress of the materials through different stages to the point of severing the individual bodies, and to the characteristic plan of preserving the sheet or strip materials in continuous or unsevered condition until the formation of the article is completed except for the final severing operation.

The means which may be employed to form the articles may vary greatly, and the order of certain of the method steps may also be varied considerably, and no importance is attached to the order of operations except where a certain operation must necessarily be performed after certain other ones.

Beyond the point of initial assembly adjacent to the rolls 34 and 35, one of the side margins which is to form the longitudinal joint is adhesively conditioned, for instance adhesive is applied to the under surface of margin 3 of sheet 1 by glue roll 36. Beyond this point the assembly cooperates with a former or mandrel 38 carried by suitable supports 39. This mandrel comprises a frame or plate 38^a, and along margins of this plate are arranged portions of a pipe 39^a which has the desired contour of the board edges, and steam is circulated through this pipe, or any other suitable heating means is provided, so that when necessary or desirable heat may be employed in connection with pressure to produce the desired edge formation.

The assembly materials which are to be edge-formed have had moisture supplied in the form of the glue applied to the under surface of strips 7, and in many cases this amount of moisture, together with the natural setting capacity of the glue, is sufficient for the forming or molding operation. Whenever necessary or desirable, however, additional moisture may be supplied to the strips or the sheet edge along the lines of edge formation to assist in the molding or forming operation.

At a suitable point in the outer margins or side portions 5 of the main strip 1 are gradually turned or folded up about the mandrel, sufficient means for this purpose being indicated in the form of angularly arranged rollers 40, and of course additional rollers or guide plates may be provided for this purpose as may be necessary. Finally the side portions 5 are brought down nearly parallel with the upper surface of the mandrel, as best shown in Fig. 3; and at about this point concaved edge pressing rollers 41 are applied to the outer edge surface of the assembly and the combined strips 1 and 7 are pressed and bent to proper form about the mandrel. At the same time, heat

may be supplied by the pipe 39^a, so that the moisture supplied is dried out and the glue is set and the edge formation made permanent. Of course the length of the mandrel over which the assembly passes in the edge forming operation may be as long as necessary to produce the desired result, and the number of pressing or forming devices such as rollers 41 may be multiplied as necessary.

In the described steps, the margins 2 and 3 have been overlapped as shown in Fig. 3, and they are now pressed together to insure adhesive engagement; for instance by an outer pressing roll 42 cooperating with a small roll 43 inserted in the mandrel. If necessary or desirable, a supporting roll 44 may be arranged below roll 43 and of course exterior to the lower face of the main sheet.

Various means may be provided for advancing the materials against retarding effect of the various forming devices. The assembly when in complete tubular form is, at a point beyond the roller 42, quite flexible, especially in its central portions; that is to say, the central portions of the main sheets or faces 4 and 5 may be easily pressed together without any injury to the assembly, and when released they will spring back substantially to the proper tubular form. This fact is taken advantage of to pass the assembly at a point beyond the roll 42 between two feed rolls 46 and 47 which are pressed together, as sufficiently indicated by spring 48 (Fig. 1), and are connected as by gears 49, and either of the roll shafts 50 and 51 may be driven in any convenient way. A very positive feed pull is thus imparted to the continuous assembly, sufficient to pull it along over the mandrel. Any other suitable feed arrangements may be employed.

The cut-off is made at a point beyond the rolls 46 and 47, and in the present instance the cutting device 55 is a rotary circular knife which is moved bodily along with the assembly at certain intervals, so that it travels at assembly speed, and then it is moved transversely across the assembly to sever the individual bodies B, after which the knife is retracted and then returned in the direction of its axis and the actions are repeated indefinitely. Any suitable cut-off mechanism may be used.

It will now be understood that by advancing materials in the continuous manner described, the bodies may be made by automatic machinery, very rapidly and cheaply, and the only further operation necessary is the insertion of the transverse reinforcements or end pieces.

The showing in a diagrammatic way of mechanism for carrying out the method does not, of course, preclude its being performed by hand or by the aid of separate mechanisms or simple implements wherever the

production is not sufficiently large to warrant the employment of complete automatic machines.

A strengthening, stiffening or hardening agent or composition may be applied to the materials, such as the shell sheet, at any convenient point in the process. For example, this treatment or application may be made after the sheet leaves the roll 30 and before it is associated with the reinforcing strip 7. When the strengthening material is in the form of a glue or glue-size, or other substance of a liquid or viscous character, it may be brushed on or otherwise applied to one or both surfaces of the sheet, and in fact the method of application of this strengthening material may be varied within wide limits.

In Fig. 1 a method of application of such material is shown which is adapted to impregnating the sheet 1 with the material, which in this particular case is a solution of sodium silicate, contained in the tank 90. The sheet or web 1 is passed under a perforated roll 91 so that the sheet is submerged in the solution, and the sheet is then carried over a series of drying rolls 92, and when desirable it may be carried over a heated drying roll 93, to which steam is applied in the manner customary for steam drier drums. By such suitable treatments, the moisture of the solution is dried out of the web, leaving it coated or impregnated with hardening material. The web then passes over a guide roll 94 to the point where, between the pressing rolls 34 and 35, it is associated with the longitudinal reinforcing strips 7, as previously fully described.

The method of producing a board of the form shown in Fig. 12, comprises the advancing of the two main sheets or strips 15, advancing continuous side strips 16, associating the strips 15 and 16 and adhesively connecting them, advancing continuous reinforcing strips 18, producing the desired edge formation by suitable operations at proper points or times in relation to other steps, and finally, when binding strips 20 are employed, advancing and adhesively securing these binding strips. The tubular assembly is then complete, and individual board bodies may be cut off in the manner previously described.

Figs. 5 and 6 show diagrammatically a continuous method for producing board bodies of the style shown in Figs. 5 and 7 previously described, most of the mechanism except the roll holders for the sheets of material and certain gluing devices being omitted, but the materials being shown in their continuous advance and formation, it being understood that the necessary operations may be performed upon the materials by any suitable mechanisms.

The continuous strip of body or shell material 60 to form the inner shell sheet, identified by the same numeral in Fig. 7, is advanced from a roll 70, and the strip is adhesively conditioned by glue roll 71, and this glue roll may extend over the entire under surface of the strip or web. A continuous strip 61 to form the outer shell sheet (Fig. 7) is advanced from a roll 72. The axes of the rolls 71 and 72 are parallel, but the rolls themselves are offset laterally so that a margin 67 of strip 60 extends laterally beyond the edge 65 of strip 61; and similarly, a margin 66 of strip 61 extends laterally beyond and below the edge 63 of strip 60 at the other side, the margins and edges being identified by the same numerals as corresponding parts in the section, Fig. 7.

The two advancing strips are brought together between pressing rolls 75 and 76, and these rolls may be offset laterally in substantial accordance with the lateral offset of the stock rolls. The overlapping surfaces of strips 60 and 61 are thus pressed in adhesive engagement.

Reinforcing strips 68 are advanced from rolls 78, and adhesive is applied to them by glue rolls 80, and they are pressed in position on the advancing assembly by pressing rolls 81 and 82, and beyond that point the assembly is bent or folded over by suitable instrumentalities, the folding process being sufficiently shown in Fig. 5, and the rounded edge formation is obtained, until finally the assembly is in the cross-sectional form shown in Fig. 7, with the shell margins 66 and 67 overlapped and adhesively connected by glue previously applied to the marginal portion 67. The assembly is then severed laterally at a point somewhere near the line 83, Fig. 5, at regular intervals, producing the individual tubular bodies B¹, the structure and characteristics of which have been sufficiently explained above.

The end plugs and intermediate reinforcements are then inserted.

I claim:

1. A method of making tubular articles of sheet material, comprising associating main body forming sheet material of substantial width and relatively narrow, spaced edge reinforcing strips, and shaping and securing the assembly in flattened tubular form.

2. A method of making tubular articles of sheet material, comprising associating main body forming sheet material of substantial width and relatively narrow, spaced edge reinforcing strips, and shaping and securing the assembly in flattened tubular form with rounded edges including said reinforcing strips.

3. A method of making flattened tubular articles of sheet material, comprising associating a main sheet of body forming material of substantial width with strips of a

- relatively narrow edge reinforcing material, shaping portions of the assembly including said strips, to produce curved body edges, and completing the flattened tubular body formation of the article. 70
4. A method of making flat-sided tubular articles of fibrous sheet material, comprising associating a main sheet of body forming material with relatively narrow, spaced strips of reinforcing material, shaping portions of the assembly including said strips to produce rounded body edges, and completing the flattened tubular body formation of the article. 75
- 15 5. A method of making tubular articles of fibrous sheet material, comprising advancing a continuous sheet of body forming material, advancing continuous strips of edge reinforcing material and adhesively securing them in spaced relation on the body sheet, and shaping the assembled materials in flattened tubular form with rounded edges including said strips. 80
- 20 6. A method of making tubular articles of sheet material, comprising advancing a continuous sheet of body forming material, advancing continuous strips of edge reinforcing material and adhesively securing them in spaced relation on the body sheet, shaping the assembled materials in flat-sided tubular form with rounded edges including said strips, and severing the continuous assembly to form individual tubular bodies. 85
- 25 7. A method of making tubular articles of sheet material, comprising advancing a continuous sheet of body material, advancing continuous strips of sheet edge reinforcing material and adhesively applying them to the body sheet, bending the assembled materials along the lines of the reinforcing strips to produce the edge formation of the completed articles, securing edges of the main sheet to complete the formation of a flattened tubular assembly, and severing the assembly transversely at regular intervals to produce individual tubular bodies. 90
- 30 8. A method of making tubular articles of fibrous sheet material, comprising advancing a continuous sheet of body material, advancing continuous strips of sheet edge reinforcing material and adhesively applying them to the body sheet, bending the assembled materials along the lines of the reinforcing strips to produce rounded edge formations of the completed article, adhesively securing edges of the main sheet to complete the formation of a flattened tubular assembly, and severing the assembly transversely at regular intervals to produce individual tubular bodies. 95
- 35 9. A method of making tubular articles of sheet material, comprising advancing a continuous sheet of body material, adhesively applying to it spaced strips of sheet edge reinforcing material, folding the assembled materials into flattened tubular form with body-sheet margins overlapped and adhesively secured together, and pressing the assembly edges to determine the edge formation of the tube. 100
- 40 10. A method of making tubular articles of sheet material, comprising advancing a continuous sheet of body material, adhesively applying to it spaced strips of sheet edge reinforcing material, folding the assembled materials into flattened tubular form with body-sheet margins overlapped and adhesively secured together, pressing the assembly edges to determine the edge formation of the tube and severing the tubular assembly transversely to produce individual tubular bodies. 105
- 45 11. A method of making tubular articles of sheet material, comprising advancing a continuous sheet of body material, advancing continuous strips of edge reinforcing material and adhesively applying them in spaced relation to the body sheet, bending the assembly portions including the reinforcing material and applying heat and pressure to secure the edge formation of the article, completing the flattened tubular formation of the assembly, and severing the assembly transversely to produce individual tubular bodies. 110
- 50 12. A method of making tubular articles of sheet material, comprising the steps of advancing a continuous sheet of body material, advancing continuous strips of edge reinforcing material and adhesively applying them in spaced relation to the body sheet, bending the assembly portions including the reinforcing material into substantially flat tubular form, and applying pressure to secure the edge formation of the article. 115
- 55 13. A method of making tubular articles of fibrous sheet material, comprising the steps of advancing a continuous sheet of body material, advancing continuous strips of edge reinforcing material and adhesively applying them to the body sheet, bending the assembly portions including the reinforcing material into substantially flat tubular form, and applying heat and pressure to secure the edge formation of the article. 120
- 60 14. A method of making tubular articles of fibrous sheet material, comprising advancing a continuous sheet of body material, advancing continuous strips of edge reinforcing material and adhesively applying them in spaced relation to the body sheet, bending the assembly portions including the reinforcing material and applying heat to secure the edge formation of the article, completing the flattened tubular formation of the assembly, and severing the assembly transversely to produce individual tubular bodies. 125
- 65 15. A method of making tubular articles of fibrous sheet material, comprising advancing a continuous sheet of body material, 130

- advancing continuous strips of edge reinforcing material and adhesively applying them in spaced relation to the body sheet, bending the assembly portions including the 5 reinforcing material and applying pressure to secure the edge formation of the article, completing the flattened tubular formation of the assembly, and severing the assembly transversely to produce individual tubular 10 bodies.
16. A method of making tubular articles of sheet material, comprising advancing a continuous sheet of body material, adhesively applying to it spaced strips of sheet edge 15 reinforcing material, applying adhesive to a margin of the body sheet, folding the assembled materials into flattened tubular form with body-sheet margins overlapped and adhesively secured together, and pressing 20 the assembly edges along the lines of said reinforcing strips to determine the edge formation of the tube.
17. A method of making tubular articles of sheet material, comprising advancing a continuous sheet of body material, adhesively applying to it spaced strips of sheet edge 25 reinforcing material, folding the assembled materials into flattened tubular form with body-sheet margins overlapped and adhesively secured together, and pressing the 30 assembly edges to determine the edge formation of the tube, severing the tubular assembly transversely to produce individual tubular bodies.
18. A method of making tubular articles of sheet material, comprising the steps of advancing a continuous sheet of body material, advancing continuous spaced strips of edge reinforcing material and adhesively applying 35 them to the body sheet, bending the assembly into substantially flat tubular form, and applying heat to secure the edge formation of the article.
19. A method of making substantially 40 tubular cloth boards or the like, comprising advancing continuous fibrous sheet material, treating the material with strengthening or stiffening material, applying spaced longitudinal edge reinforcing strips and folding 45 the assembled materials into flattened tubular form.
20. A method of making substantially 50 tubular cloth boards or the like, comprising advancing continuous fibrous sheet material, treating a surface of the material with strengthening or stiffening material, adhesively applying spaced longitudinal edge reinforcing strips, folding the assembled 55 materials into flattened tubular form, and severing the assembly transversely.
21. A method of making cloth boards and 60 similar tubular articles of sheet fibrous material having flat parallel sides substantially spaced apart and connected by continuous edge portions, comprising advancing 65
- ing a continuous sheet of fibrous body material of substantial thickness and stiffness, adhesively securing to the sheet continuous strips of fibrous sheet reinforcing material in spaced relation corresponding to longitudinal edges of the article to be produced, and bending the body sheet to produce the stated tubular formation with the longitudinal edges of the board including the reinforcing strips. 70
22. A method of making cloth boards and similar tubular articles of sheet fibrous material having flat parallel sides substantially spaced apart and connected by continuous edge portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, and pressing the edges to shape and fix the edge formation. 75
23. A method of making cloth boards and similar articles of sheet fibrous material having flat parallel sides substantially spaced apart and connected by continuous edge 80 portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, 85 bending the body sheet to produce the stated tubular formation with the longitudinal edges of the board including the reinforcing strips, and pressing the edges to shape and fix the edge formation. 90
24. A method of making cloth boards and similar tubular articles of sheet fibrous material having flat parallel sides substantially spaced apart and connected by continuous edge 95 portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, and adhesively connecting longitudinal margins of the body sheet. 100
25. A method of making cloth boards and similar tubular articles of sheet fibrous material having flat parallel sides substantially spaced apart and connected by continuous edge 105 portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, and applying tractive pressure to the opposite flat sides of the formed board tube at substantially its mid-width with accompanying collapse of the central portion of the tube, to advance the material without permanent deformation of the tube-cross-section. 110
26. A method of making cloth boards and similar tubular articles of sheet fibrous material having flat parallel sides substantially spaced apart and connected by continuous edge 115 portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, and applying tractive pressure to the opposite flat sides of the formed board tube at substantially its mid-width with accompanying collapse of the central portion of the tube, to advance the material without permanent deformation of the tube-cross-section. 120
27. A method of making cloth boards and similar tubular articles of sheet fibrous material having flat parallel sides substantially spaced apart and connected by continuous edge 125 portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, and applying tractive pressure to the opposite flat sides of the formed board tube at substantially its mid-width with accompanying collapse of the central portion of the tube, to advance the material without permanent deformation of the tube-cross-section. 130

- terial having flat parallel sides substantially spaced apart and connected by continuous edge portions, comprising advancing a continuous sheet of fibrous body material of substantial thickness and stiffness, adhesively securing to the sheet continuous strips of fibrous sheet reinforcing material in spaced relation corresponding to longitudinal edges of the article to be produced, bending the body sheet to produce the stated tubular formation with the longitudinal edges of the board including the reinforcing strips, adhesively connecting longitudinal margins of the body sheet, and severing the continuous tube transversely at regular intervals.
26. A method of making cloth boards and similar tubular articles of paper or cardboard, having flat parallel sides substantially spaced apart and connected by continuous edge portions, comprising advancing a continuous sheet of cardboard body material of substantial thickness and stiffness, adhesively securing to the sheet continuous strips of cardboard reinforcing material in spaced relation corresponding to edges of the article to be produced, bending the body sheet to produce the stated tubular formation with the longitudinal edges of the board including the reinforcing strips, pressing the edges to shape and fix the edge formation, and adhesively securing longitudinal margins of the body sheet.
27. A method of making cloth boards and similar tubular articles of paper or cardboard, having flat parallel sides substantially spaced apart and connected by continuous edge portions, comprising advancing a continuous sheet of cardboard body material of substantial thickness and stiffness, adhesively securing to the sheet continuous strips of cardboard reinforcing material in spaced relation corresponding to edges of the article to be produced, bending the body sheet to produce the stated tubular formation with the longitudinal edges of the board including the reinforcing strips, pressing the edges to shape and fix the edge formation, adhesively securing longitudinal margins of the body sheet, and applying tractive pressure to the opposite flat sides of the formed board tube at substantially its mid-width with accompanying temporary collapse of the central portion of the tube, to advance the material without injurious deformation of the tube edges.
28. A method of making tubular articles from sheet material, comprising securing separated strips upon a sheet of material and shaping the assembly along areas in proximity to the strips to produce a flattened tube.
29. A method of making tubular articles from sheet material, comprising securing separated strips upon a sheet of material and shaping the assembly along areas in proximity to the strips to produce a flattened tube, and shaping the assembly along areas in proximity to the strips to produce a flattened tube, and securing together longitudinal margins of the sheet.
30. A method of making tubular articles from sheet material, comprising securing separated strips upon a sheet of material and shaping the assembly along areas in proximity to the strips to produce a flattened tube, and severing the tubular assembly transversely at intervals to produce individual tubular articles.
31. A method of producing tubular articles from sheet material, comprising advancing a web of bendable sheet material of substantial thickness and stiffness, applying and securing to the web spaced strips of bendable sheet material, and bending the combined materials along areas including the applied strips to produce a flattened tube.
32. A method of producing tubular articles from sheet material, comprising advancing a web of bendable sheet material of substantial thickness and stiffness, applying and securing to the web spaced strips of bendable sheet material, bending the combined materials along areas including the applied strips to produce a flattened tube, and severing the tubular assembly transversely at intervals to produce individual tubular articles.
33. A method of producing tubular articles from sheet material, comprising advancing a web of bendable sheet material of substantial thickness and stiffness, advancing strips of flexible sheet reenforcing material and securing them adhesively to a face of the web in spaced relation, and bending the combined materials along longitudinal areas comprising the reenforcing strips to produce a flattened tube.
34. A method of producing tubular articles from sheet material, comprising advancing a web of bendable sheet material of substantial thickness and stiffness, advancing strips of flexible sheet reenforcing material and securing them adhesively to a face of the web in spaced relation, bending the combined materials along longitudinal areas comprising the reenforcing strips to produce a flattened tube, and severing the tubular assembly transversely at intervals to produce individual tubular articles.
35. A method of making tubular articles, comprising feeding sheet material, applying separated reinforcements to said sheet, bending the sheet at the reinforcements, and advancing the assembly so produced by tractive contact applied between the reinforcements.
36. A method of making tubular articles, comprising feeding sheet material, applying separated reinforcements to said sheet, bending the sheet at the reinforcements, advancing

ing the assembly so produced by tractive contact applied between the reenforcements, and severing the tubular assembly transversely at intervals to produce individual articles.

37. A method of making tubular articles, comprising feeding flexible sheet material, applying separated reenforcements to said sheet, bending the sheet at the reenforcements and shaping it in tubular form, and advancing the assembly so produced by tractive contact applied between the reenforcements.

38. A method of making tubular articles, comprising feeding flexible sheet material, applying separated reenforcements to said sheet, bending the sheet at the reenforcements and shaping it in tubular form, and applying tractive force to opposite faces of the formed tube between the reenforcements to advance the combined materials.

39. A method of making tubular articles, comprising feeding flexible sheet material, applying separated reenforcements to said sheet, bending the sheet at the reenforcements and shaping it in tubular form, and applying tractive force to opposite faces of the formed tube between the reenforcements with accompanying temporary deformation of the tube to advance the combined materials.

40. A method of making tubular articles, comprising feeding flexible sheet material, applying separated reenforcements to said sheet, bending the sheet at the reenforcements and shaping it in tubular form, and applying tractive pressure at opposite sides of the formed tube between the reenforcements with accompanying temporary deformation of the tube and contact of its members to advance the combined materials.

41. A method of making tubular articles, comprising feeding flexible sheet material, applying separated reenforcements to said

sheet, bending the sheet at the reenforcements and shaping it in tubular form, advancing the assembly so produced by tractive contact applied between the reenforcements, and severing the tubular assembly transversely at intervals to produce individual tubular articles.

42. A method of making tubular articles, comprising feeding flexible sheet material, applying separated reenforcements to said sheet, bending the sheet at the reenforcements and shaping it in tubular form, and severing the tubular assembly transversely at intervals to produce individual tubular articles.

43. A method of making tubular articles, comprising feeding flexible sheet material, applying separated reenforcements to said sheet, bending the sheet at the reenforcements and shaping it in tubular form, applying tractive force to opposite faces of the formed tube between the reenforcements with accompanying temporary deformation of the tube to advance the combined materials, and severing the tubular assembly transversely at intervals to produce individual tubular articles.

44. A method of making tubular articles, comprising feeding flexible sheet material, applying separated reenforcements to said sheet, bending the sheet at the reenforcements and shaping it in tubular form, applying tractive pressure at opposite sides of the formed tube between the reenforcements with accompanying temporary deformation of the tube and contact of its members to advance the combined materials, and severing the tubular assembly transversely at intervals to produce individual tubular articles.

Signed at New York city in the county of New York and State of New York this 29th day of March, A. D. 1922.

HARRY BRIDGMAN SMITH.
